UNITED STATES PATENT OFFICE.

GEORGE D. HARTZELL, OF FORT RECOVERY, OHIO.

DESIGN FOR A GRAVE-VAULT.

SPECIFICATION forming part of Design No. 25,446, dated April 28, 1896.

Application filed January 27, 1896. Serial No. 577,070. Term of patent 14 years.

To all whom it may concern:

Be it known that I, GEORGE D. HARTZELL, a citizen of the United States, residing at Fort Recovery, in the county of Mercer and State of Ohio, have invented and produced a new and original Design for Grave-Vaults; and I do declare the following to be a full, clear, and exact description of the same, reference being had to the accompanying drawing, forming a part thereof.

The leading feature of my design consists in a grave-vault having a general form of an oblong parallelepiped, all of whose lines and angles are straight and unbroken, whose sides and ends have therein the sunk panels shown at A and C, respectively, in the accompanying drawing, said panels being of

general rectangular form, with rounded corners and bevel edges, and whose cover portion D is of less length and width than its body portion, portions of whose upper edges are thereby exposed to form a surrounding horizontal ledge or flange portion E. In said top portion near one end is a conical opening B. 25

What I claim is—

The design for a grave-vault, substantially as herein shown and described.

In testimony whereof I affix my signature in presence of two witnesses.

GEORGE D. HARTZELL.

Witnesses:

R. W. RANDLE,
P. M. HEARN.
